UNITED STATES PATENT OFFICE.

HERMANN FISCHER, OF NEW YORK, N. Y., ASSIGNOR TO C. BRANDES, INC., OF NEW YORK, N. Y., A CORPORATION OF NEW YORK.

SOUND-PRODUCING DIAPHRAGM.

Application filed October 24, 1922. Serial No. 596,630.

To all whom it may concern:

Be it known that I, HERMANN FISCHER, a citizen of Russia, residing at New York, in the county of New York, State of New York, have invented certain new and useful Improvements in Sound-Producing Diaphragms; and I do hereby declare the following to be a full, clear, and exact description of the invention, such as will enable others skilled in the art to which it appertains to make and use the same.

This application is a continuation in part of my application Serial No. 575,246, filed July 15, 1922.

15 The invention relates to sound producing diaphragms and has for its object the provision of an improved diaphragm whereby greater accuracy in the reproduction of musical and other tones may be accomplished: More particularly, the object in view is to provide a diaphragm for use either in telephones or talking machines, which will produce the lower notes of the musical scale in more correct proportionate 20 volume, as compared to the volume of the higher notes, than can be obtained with the ordinary diaphragm, such as is regularly used for telephone receivers.

When a diaphragm of, say, a telephone receiver is proportioned so as to have a natural period of the order of the higher notes of the musical scale, it will reproduce these notes with comparative accuracy, but as is well known, the lower notes are bound 25 to be greatly attenuated. This, as is also well known, is due to the fact that the diaphragm offers increasing inertia, as the difference between the period of the forced vibrations and the natural period increases.

30 The present invention takes account of this inability of the ordinary diaphragm to reproduce in proportionate volume both the upper and lower notes of the musical scale and provides a diaphragm which accomplishes in large measure the object stated.

The invention is based on the knowledge of the fact that the particular form of the so-called *f*-holes in violins is a factor of vital importance—experience having shown 35 that the best results apparently cannot be obtained in a violin with any other form of opening.

According to the preferred form of the

invention, there is provided a sound producing diaphragm having one or more *f*-holes. 40 Such a diaphragm, it has been found, gives materially improved results.

The specific form of diaphragm shown in the accompanying drawing, and described hereinafter, is provided with two *f*-holes 45 and is adapted particularly for use in a single pole telephone receiver. The invention is not, however, limited to any particular number of *f*-holes, nor to the exact 50 shape of *f*-holes shown.

In the drawing, Fig. 1 shows a diaphragm having two *f*-holes, in accordance with the preferred form of the invention, and Fig. 2 is a cross sectional view of a single pole telephone receiver, of which the diaphragm 55 of Fig. 1 forms a part.

The diaphragm indicated by reference character 1 is provided with two apertures 1^a and 1^b, which corresponds closely with the so-called *f*-holes, usually provided in violins and some other musical instruments. According to the theory of action of this diaphragm, which is believed to be well founded, the lower notes of the musical 60 scale are accentuated by the projecting portions 1^c, 1^d, 1^e and 1^f, which apparently have a lower natural period than the remainder of the diaphragm.

The essential element of the invention resides in the provision of an aperture or 65 apertures which define one or more projecting portions of varying width, 1^c, 1^d, 1^e and 1^f.

In Fig. 2, there is shown a cross-sectional view of an ordinary single pole watch-case 70 telephone receiver, including a diaphragm like that of Fig. 1. In this figure, 2 is a casing, in the center of which is mounted an electromagnet 3, having a polepiece 3^a in close juxtaposition to the diaphragm 1, as 75 in the usual telephone construction. The casing 2 is provided with a screw thread 2^a, by which a receiver cap 4 is secured thereto.

While the theory propounded above relating to the action of the diaphragm here described is believed to be correct, it is not at all essential to a complete disclosure of the invention and is not to be construed as imposing any limitation thereon.

I claim:

An electromagnetic sound reproducer,

comprising in combination a casing, an electromagnetic mechanism carried therein, a diaphragm mounted in said casing in operative relation with said electromagnetic mechanism and adapted to be operated at the center thereof by said electromagnetic mechanism, said diaphragm containing a pair of $\mathcal{S}$ -shaped apertures symmetrically

located on opposite sides of the center of said diaphragm in parallel lines substantially spaced apart and equidistant from the point of actuation of said diaphragm by said electromagnetic mechanism. 10

In testimony whereof I affix my signature.

HERMANN FISCHER.
